UNITED STATES PATENT OFFICE.

PAUL YUKANIS, OF CHICAGO, ILLINOIS.

LOCK.

1,284,540.

Specification of Letters Patent. Patented Nov. 12, 1918.

Application filed June 21, 1917. Serial No. 178,028.

To all whom it may concern:

Be it known that I, PAUL YUKANIS, a citizen of the United States of America, and resident of Chicago, Cook county, Illinois, have invented a certain new and useful Improvement in Locks, of which the following is a specification.

My invention relates to door locks in general, but more particularly to those for use in conjunction with sliding doors, such as garage doors, or for any other purpose.

Generally stated, the object of my invention is to provide a novel and comparatively inexpensive form of door lock which can be used on garage doors, or for other purposes, and which can be easily varied so that the keys thereof will all be of slightly different shapes, whereby the key of one lock will not operate any of the other locks, at least so far as a certain number of the locks is concerned, and whereby sliding or other doors may be provided with locks which will afford ample protection.

Another object is to provide a lock of this kind in which inner means are provided for the operation of the lock, without using the key, so that should the door of the garage be closed, after the owner enters, the lock can then be operated from the inside to unlock the door.

It is also an object to provide certain details and features of construction and combinations tending to increase the general efficiency and desirability of a door lock of this particular construction.

To these and other useful ends, my invention consists in matters hereinafter set forth and claimed.

In the accompanying drawings:—

Fig. 1 is a horizontal section of a portion of a sliding door and the adjacent portion of the door-frame, showing a lock therefor embodying the principles of my invention.

Fig. 2 is an inside elevation of said door and door-frame, and said lock, showing the door partly open.

Fig. 3 is a front elevation of said lock, with the outer plate or cover thereof removed, showing the mechanism in position to receive the stationary catch on the door-frame, it being understood that the lock-mechanism is secured to the sliding door.

Fig. 4 is a view similar to Fig. 3, but showing the mechanism in the condition thereof necessary for releasing said catch on

the door-frame, after the key has been turned to unlock the door, certain parts of the mechanism being omitted in both of these figures (Fig. 3 and Fig. 4) in order to bring into view certain other parts.

Fig. 5 is a view similar to Fig. 4, but showing said omitted parts in position, and showing the mechanism operated by the inner means for unlocking the door, instead of by the key.

Fig. 6 is a vertical section on line 6—6 in Fig. 3.

Fig. 7 is a side elevation of the key.

Fig. 8 is a lower edge view of one of the plates of the mechanism engaged by the key.

As thus illustrated, my invention comprises a flat lock-casing A secured to the sliding door B in position to receive the stationary catch C on the stationary door-frame D, the door-construction being of any suitable or desired character. Said catch is preferably tapered and provided with a vertical opening e to engage the mechanism within the casing. When applied as shown, the device is in the nature of a rim-lock, but it will be understood that the invention can be used in the form of a mortise-lock, or any other form of lock, if such is desirable or necessary.

The casing A has its end toward the catch C provided with an opening a to receive said catch, and the mechanism comprises a pair of pivoted jaws E and F which are pivoted to the casing at e and f, which are provided with hook-shaped end-portions 1 and 2 for engaging the opening e in the stationary catch. The two jaws are in the nature of a pair of levers, and are provided with pins 3 and 4 at their other ends. A plate G has one end-portion mounted on the pivot f and its other end mounted on the pivot 5 of the rocking plate H, said plate G having its lower edge provided with a flange g which extends under the jaw or lever F, whereby the plate G is stationary. The plate H is provided with cams 6 and 7 for engaging, respectively, the pins 3 and 4, so that when the plate H is rocked from the position shown in Fig. 3 to the position shown in Fig. 4 the jaws E and F will have their hook-shaped ends 1 and 2 separated. The plate H is also provided at its lower edge with a cam-portion 8 for engagement with the long lug 9 of the key I, which key is adapted to be inserted through the key-hole 10 in the front plate of the lock and into engagement

with the stationary stud 11 on the inner or back plate of the lock-casing. The shortest lug 12 of the key passes under the flange *g* of the plate *G*; so that the key can rotate to the position shown in Fig. 4, thereby to unlock the door. The unlocking operation causes a separation of the hook-shaped end-portions 1 and 2 against the pressure of the springs 13 and 14 which bear against the said jaws. The mechanism, however, is self-retained in the condition shown in Fig. 4, as when the parts are in these positions the pressure of the cam 8 against the lug 9 of the key is in a direction to keep the latter against the stop 15 of the lock-casing. To enable the lug 12 to pass below the plate *G*, the flange *g* of said plate is provided with a notch 16, and the lower edge of this plate is received by the notch 17 in said key. A short plate *J* is placed flatwise against the plate *H*, on the pivots *f* and 5, and this plate has its lower edge provided with a notch *j* to receive the notch 18 of said key when the latter is turned in the direction to unlock the door. A fourth plate *K*, for this particular lock, is then placed on the plate *J*, on the pivots *f* and 5, and this plate *K* has its lower edge provided with a notch *k* to receive the lug 19 of the key, when the latter is turned to unlock the door.

Of course, the lock will operate without the plates *G*, *J* and *K*, and in such case only the lug 9 on the key will be necessary. These additional plates, however, make it more difficult to pick the lock, and necessitate the use of a special key, having the shape shown in Fig. 7, and the keys of other shapes will not operate this particular lock. One or more of said plates can be omitted, or additional similar plates can be employed, as may be desired, necessitating keys of different shapes for the different locks.

As thus described, the lock is operable only from the outside through the medium of a key inserted through the key-hole 10, which latter is in alignment with an opening in the door. In order, however, that the lock may be operated from the inside, should the door be closed after the owner of the garage has entered, the lock-casing *A* is provided at one end thereof with a movable section 20 mounted on an arm 21 which is pivoted at 22 inside of the casing. This section 20 is provided with a screw or other engaging portion 23 for engaging the upper end-portion 24 of the plate *H*, so that inward pressure of this section, in the manner shown in Fig. 5, will operate the plate *H* to unlock the door. This section 20 is not noticeable, as the exterior of the lock-casing may be of such character that this provision will not be obvious and will only be known, for example, to the owner of the garage. A spring 25 of any suitable character, can be provided for engaging the section 20, to hold the lat-

ter normally closed, and when this section is pushed inward the jaws *E* and *F* will be separated to release the catch *C* on the door-frame. Springs 26, 27 and 28 are applied, respectively, to the pivots *e*, *f* and 5, to hold the parts in place, it being understood that the outer ends of these coil springs bear against the front plate of the lock-casing. Thus sufficient space is provided inside of the casing for the addition of other plates, similar to the plates *J* and *K*, for keys of different shapes, thereby permitting the necessary variations in the construction of the lock, for the different keys, with very little additional expense. Also, the lock could easily be changed, for a key of a different shape, by substituting different plates for those shown, whenever this is necessary or desirable.

It will be understood, of course, that the lock-casing *A* and the catch *C* can be interchanged so that the catch will be movable and the lock-casing stationary. Also, the mechanism can be applied to divided doors, the casing *A* being mounted on one section of the door, and the catch *C* being mounted on the other section of the door, so that the catch and the lock-mechanism will come together when the two sections of the door are brought together or closed. The catch *C* is adapted to be forcibly wedged between the two hook-portions 1 and 2, when the door is closed, so that these hook-portions will enter the opening *c* in said catch, thereby holding the door in locked condition.

What I claim as my invention is:—

1. A door lock comprising a casing having a key-hole, a catch outside the casing, pivoted means inside to engage said catch, when the catch enters the casing, an oscillating element having cam-engagement with said means, so that operation of said element from normal position disengages said means from said catch, a pivot for said element, and a key insertible through said key-hole to operate said element and means, said element having a cam to engage said key, so that said key and said element turn in opposite directions when the door is unlocked.

2. A door lock comprising a casing having a key-hole, a catch outside the casing, pivoted means inside to engage said catch, when the catch enters the casing, an oscillating element having cam-engagement with said means, so that operation of said element from normal position disengages said means from said catch, a pivot for said element, and a key insertible through said key-hole to operate said element and means, said element having a cam to engage said key, so that said key and said element turn in opposite directions when the door is unlocked, said means including a pair of jaws pivoted between their ends, and said element being a plate provided with a cam for the rear end.

of each jaw, whereby the jaws are separated by pivotal motion of said element to draw said rear ends toward each other, and springs to press said jaws together, said catch being 5 adapted for wedging insertion between said jaws.

3. The structure of claim 1, said means comprising a pair of pivoted members, said element being a plate disposed flatwise 10 against the sides of said members, and one or more stationary plates adjacent said element to determine the shape of said key, which plates are mounted on the pivots of said element and one of said members.
- 15 4. The structure of claim 2, and one or more plates mounted in the front of said element to determine the shape of said key.
5. The structure of claim 1, and a movable device for engaging said element to unlock the door from the inside thereof, said key being insertible from the outside only.
- 20 6. The structure of claim 2, and a device for tilting said element to unlock the door from the inside thereof, said element having a cam to engage said device.
- 25 7. A door lock comprising a casing having a key-hole, a catch outside the casing, pivoted means inside to engage said catch, when

the catch enters the casing, an oscillating element having cam-engagement with said means, so that operation of said element from normal position disengages said means from said catch, a pivot for said element, and a key insertible through said key-hole to operate said element and means, said element having a cam to engage said key, so that said key and said element turn in opposite directions when the door is unlocked, said casing having a movable section for operating said element to unlock the door from 40 the inside.

8. The structure of claim 1, springs to retain said means in normal position to receive said catch, and means to hold said key in position to retain said means in open position against the action of said springs.

9. A door lock provided with an outer casing, having an opening in the wall thereof, and a movable section which fits said opening and which is movable inwardly for 50 operating the lock, and mechanism inside the casing for operation by said movable section to unlock the door from inside.

Signed by me at Chicago, Illinois, this 16th day of June, 1917.

PAUL YUKANIS.
